UNITED STATES PATENT OFFICE.

MORTIMER NORDEN, OF NEW YORK, N. Y.

DESIGN FOR AN ELECTRIC SIGN.

57,852.

Specification for Design. Patented May 10, 1921.

Application filed November 15, 1920. Serial No. 424,304. Term of patent 7 years.

To all whom it may concern:

Be it known that I, MORTIMER NORDEN, a citizen of the United States, residing at the borough of Manhattan, in the city, county, and State of New York, have invented a new, original, and ornamental Design for an Electric Sign, of which the following is a specification, reference being had

to the accompanying drawing, forming part thereof.

The figure is a front elevation of an electric sign, showing my new design.

I claim:

The ornamental design for an electric sign, as shown.

MORTIMER NORDEN.
